(57) **CLAIM**

The ornamental design for a portable digital media player case, as shown and described.

DESCRIPTION

FIG. 1 is a front-elevational view of a portable digital media player case according to the invention;

FIG. 2 is a top-plan view of the case of the invention;

FIG. 3 is a bottom-plan view of the case of the invention;

FIG. 4 is a left side-elevational view of the case of the invention;

FIG. 5 is a right side-elevational view of the case of the invention, showing a winder in a closed storage position;

FIG. 6 is a rear-elevational view of the case of the invention, in which the winder is shown in the closed storage position;

FIG. 7 is a top plan view of the case with the winder shown in an open position;

FIG. 8 is a front elevational view of the case with the winder shown in an open position;

FIG. 9 is a rear elevational view of the case with the winder shown in an open position;

FIG. 10 is a front and right side perspective view of the case of the invention with the winder in the open position and an earbud cord wrapped around the winder;

FIG. 11 is a rear and right side perspective view of the case of the invention with the winder in the open position and a belt clip attached; and

FIG. 12 is an exploded view of the case of the invention; and,

FIG. 13 is a rear, top and left-side perspective view of the case of the invention showing a stand at the rear.

The broken line showing of environment in the drawings is included for the purpose of illustrating only and forms no part of the claimed design.
